H. O. RUGH,
RELAY SYSTEM,
APPLICATION FILED MAY 12, 1919.

1,337,797.

Patented Apr. 20, 1920.

INVENTOR Harry O Rugh

Franklin, Pa.
City:

UNITED STATES PATENT OFFICE.

HARRY O. RUGH, OF CHICAGO, ILLINOIS.

RELAY SYSTEM.

1,337,797.

Specification of Letters Patent. Patented Apr. 20, 1920.

Application filed May 12, 1919. Serial No. 296,356.

To all whom it may concern:

Be it known that I, HARRY O. RUGH, a citizen of the United States of America, residing at Chicago, in the county of Cook 5 and State of Illinois, have invented certain new and useful Improvements in Relay Systems, of which the following is a full, clear, and exact description, such as will enable others skilled in the art to which my 10 invention appertains to make and use the same.

My invention relates to relay systems, and more particularly to relay signaling systems, and is particularly adapted for use 15 in a telegraph system, or other similar signaling system. A principal object of my invention is to provide for the breaking of a local energizing circuit of a telegraph sounder or similar signal device, after a 20 predetermined length of time, even if the controlling main line circuit which initiates the closure of the said energizing local circuit is continuously closed.

In the system of my invention, the usual 25 telegraph sounder may readily be replaced with a buzzer tone signal device, and it is a further object of my invention, therefore, to provide a system wherein buzzer tone signals may be given without the consequent annoyance of having the buzzer 30 continuously operated when the main telegraph circuit is continuously closed, as for instance after the sending of a message. Such a continuous buzzer signal would be 35 quite annoying, and it is a further object of my invention to provide in such a system, an audible tone signaling device adapted to operate under the control of a standard unmodified telegraph line relay, to faithfully 40 produce in tone audible signals, the dots and dashes of the Morse telegraphic code, at the same time the signal device being rendered entirely inoperative during the intervals when telegraphic signals are not 45 being transmitted or received. A further object is to effect a current saving when messages are not being sent over the telegraph line.

Other objects of my invention are to so 50 construct the mechanism that it will be positive in operation, inexpensive to manufacture, and when adjusted, to be adapted to remain in a proper adjustment for long periods of time without attention.

55 Other objects of my invention and the invention itself will be made more apparent

to those skilled in the art by the following description of the same in which reference will be had to the drawing accompanying this specification.

60

In the drawing at L, I show a telegraphic line relay serially included with a telegraph key, in series with the conductors 1 and 2 of a telegraph line, together with a source of current B. The line conductors 65 1 and 2 may be, for the purpose of describing this invention, understood to lead to a distant station having a like key and line relay as well as other associated controlled apparatus as illustrated for the station A. A vibratory tone signal device is shown at V, having a sonorous member S, adapted to be operated by the impact of an armature-hammer H, striking on an anvil rod AR, which is shown as being operatively connected to a diaphragm D, of the 70 said sonorous member. The arrangement is such that when the armature-hammer H, strikes the anvil member AR, the diaphragm D, is agitated and the sonorous 75 member S, is caused to emit sound vibrations producing a tone, the volume of the tone being amplified by an amplifying horn AH. An electro-magnet E, and circuit breaking contacts C, are provided to control the vibratory movement of the armature-hammer H.

A slow operating relay mechanism RM, is provided having an electro-magnet M, armature MA, and normally closed contacts 90 CT. A retractile spring 3, is provided for the armature H, of the device V, to normally maintain the contacts C, closed, and likewise a retractile spring 4, is provided for the armature MA, of the mechanism 95 RM, to normally maintain the contacts, CT, closed.

The construction of the relay, RM, is such that it is of the type known in the art, as a slow operating relay, the armature only 100 responding to current impulses of normal strength which are continued for a considerable period.

I find that a relay constructed substantially as shown, in the drawing at RM, may 105 be made to operate sufficiently slow, that it will fail to operate on current impulses corresponding in length to the ordinary dots and dashes of the Morse code, although responding readily, upon a continued 110 closure of the circuit, which continued closure produces a current impulse of con-

siderably greater length than any current impulse responsive to the dot or dash circuit closures effected to produce the Morse code signals.

5 The system of my invention operates as follows: Assume that the telegraph key K, is continuously closed and a similar key included in the circuit with the line conductors 1 and 2 at the distant station, not 10 shown but understood, is operated to close the line circuit for very short intervals, such as for instance would be the case when the dots and dashes of the Morse code are being "sent." Due to such an operation of 15 the distant key, the armature LA, of the line relay will be vibrated substantially in unison with the sending key to produce intermittent closures of the line relay contacts CL. These closures produce a sounding of 20 the signal by the sonorous member S, of the audible tone signal V, as each closure completes a circuit for the winding of the actuating electro-magnet E, thereof. This circuit may be traced as follows:—From 25 the positive pole of the source of current, BY, through the closed contacts CL, of the relay L, circuit conductor 5, the winding of the electro-magnet E, normally closed contacts C of the electro-magnet E, 30 circuit conductor 6, normally closed contact CT of the relay mechanism RM, circuit conductor 7, circuit conductor 8 to the negative pole of the source of current BY.

A multiple circuit across the conductors 35 5 and 8, including the winding of the electro-magnet M, is provided, to energize this electro-magnet from the source of current BY, in unison with the energizations of the signal device V. But the relay mechanism 40 RM, being slow operating though relatively quick releasing, the brief energizations of this electro-magnet M, during the telegraphic sending period, will not be of sufficient duration to cause the electro-magnet 45 to attract its armature MA, so that the contacts CT, in the circuit of the magnet E, of the signal device V, will not be broken. Thus, the signal device remains operatively connected in circuit with the controlling 50 contacts CL, and the source of current BY, due to the inactivity of the armature MA, of the slow operating relay mechanism RM; this during the "sending" period.

But upon a prolonged closure of the contact CL, as produced, for instance, by the final closure of the distant telegraphic key after the sending of the message, the relay mechanism RM, will be operated due to the prolonged energization of its magnet 60 M, included in the circuit with the controlling contact CL, of the source of current BY.

The operation of the relay mechanism RM, causes the armature MA, to be attracted, moving from its normal circuit 65 closing position to its circuit opening po-

sition disables the signal device V, due to its being disconnected from the source of current.

Now the signal device V, may be replaced by an ordinary telegraph sounder if desired, the sounder or tone signal device being simply interchangeable. My invention provides for the use of either type of signal device. The magnet winding of the relay mechanism RM, is of relatively high 75 resistance as compared with that of the signal device E, therefore a considerable saving in current consumption is to be had, due to the opening of the contacts CT, in the circuit of the signal device in the intervals between telegraphic signal periods. 80

Having now described a particular embodiment of my invention, I desire to state that I am aware that numerous and extensive departures may be made from the said 85 embodiment herein illustrated and described, without departing from the spirit of my invention, but what I claim as my invention is defined in the following claims:—

1. In a telegraph system, the combination with, a main line circuit, of a local circuit, a line relay, a winding therefore included in the main line circuit, a signal device, a slow pick-up relay, a winding and contacts 95 for the said slow relay, multiply connected branch circuits for the slow relay winding and the said signal device, said signal device branch circuit including said slow relay contacts. 100

2. In a telegraph system, the combination with a main line relay, of a local circuit having two branches under the control of the said relay, a slow pick-up relay, a winding therefor included in one of the said 105 branches, and an electroresponsive device and contacts of said slow relay serially included in said other branch.

3. In a telegraph system, the combination with a main line relay, of a branched local 110 circuit, a source of current serially included in a main conductor of the said local circuit, an electro-responsive device in one of the branches thereof, a slow responding relay in another branch, an armature for the main 115 line relay, an armature for the slow responding relay, said device being under the joint control of said main line and slow responding relay armatures.

4. In a signaling system, the combination with a telegraph signal device, of a slow responding relay, a common source of energizing current for the said device and said relay, a main line relay, contacts of said line relay included in circuit with the said 125 source to control the said device and the said relay, and means under the control of the said relay controlling the said device.

5. In a signaling system, the combination with a main relay, of a slow responding 130

- and relatively quick retracting relay under the control of the said main relay, a normally closed energizing circuit for the said main relay, means to interrupt and reclose 5 the said circuit for short or long intervals, an electro-responsive device normally out of the control of the said main relay, said device and the winding of the said controlled relay being in multiply connected 10 circuits, and means responsive to a rupturing of the main line circuit to restore the control of the said main relay over the said controlled relay.
6. In a telegraph system, the combination 15 with a main line relay, of a branched local circuit, a source of current serially included in a main conductor of the said local circuit, an electro-responsive device in one of the branches thereof, a slow responding re- 20 lay in another branch, an armature for the main line relay, an armature for the slow responding relay, said device being under the joint control of said main line and slow
- responding relay armatures, said last named armature being under the control of the 25 other armature.
7. In a telegraph system, the combination with a main line relay, an armature therefor, a slow pick-up relay, an electro-responsive device, an energizing circuit for the 30 slow pick-up relay, an energizing circuit for the said device, said device being adapted to give a continuous signal as long as its energizing circuit is closed, an armature for the slow pick-up relay, a set of contacts controlled by the pick-up relay armature and a set of contacts controlled by the main line relay armature serially included in the said electro-responsive device energizing circuit, 35 said slow pick-up relay circuit being under 40 the control of the said main line relay armature.

In witness whereof I hereunto subscribe my name this 9th day of May A. D. 1919.

HARRY O. RUGH.
